UNITED STATES PATENT OFFICE.

ABRAHAM KELLER, OF SAN FRANCISCO, CALIFORNIA.

SAFETY DEVICE FOR DOORS.

1,414,286.

Specification of Letters Patent. Patented Apr. 25, 1922.

Application filed January 24, 1921. Serial No. 439,447.

To all whom it may concern:

Be it known that I, ABRAHAM KELLER, a citizen of the United States, residing at San Francisco, in the county of San Francisco and State of California, have invented new and useful Improvements in Safety Devices for Doors, of which the following is a specification.

This invention relates to improvements in door attachments and has particular reference to a safety device adapted to be applied to various types of doors, particularly to the doors of railway passenger coaches.

The primary object of this invention is to provide a safety device of the character described which can be readily attached to a door in order to prevent the slamming of the door, which not only shortens the life of the door and the frame structure but often causes injury to a person in close proximity to the door.

Another object of this invention is to provide a safety device adapted to operate upon movement of the door knob and which can be readily applied to various types of doors without materially altering the construction thereof.

A further object to this invention is to provide a device of the above mentioned character which is simple in construction, inexpensive to manufacture, easily assembled and disassembled, strong, durable and highly efficient.

Other objects and advantages of the invention will be apparent during the course of the following description:

Great annoyance has been experienced by the repeated slamming of doors, particularly those of railway passenger coaches, with a consequent disastrous effect not only to the door and door frame, but oftentimes to travellers who have been caught in the slamming doors. To overcome these objections, I have devised the present safety attachment, which will prevent a door to which it is applied from slamming, and thereby supply a long needed want.

In the accompanying drawings forming a part of this specification and in which like numerals are employed to designate like parts throughout the same,

Figure 1 is a side elevation of my improved attachment partly in section, as applied to a door, the view being taken on the line 1—1 of Figure 2,

Figure 2 is a vertical sectional view of the same, taken on the line 2—2 of Figure 1,

Figure 3 is a sectional view of the control arm and its associated elements, the view being taken on the line 3—3 of Figure 2, 60

Figure 4 is a sectional view taken on the line 4—4 of Figure 1, and

Figure 5 is a sectional view of the attachment shown applied to a projecting door.

Figure 6 is a sectional view of the attachment as applied on the face of the door. 65

In the drawings wherein for the purpose of illustration is shown a preferred embodiment of my invention, the numeral 10 designates a door equipped with an outer side 70 11 and an inner side 12. Penetrating the body of the door is a square spindle 13, which has provided on each extremity the usual knobs 14 and 14', and adjacent one extremity a grooved escutcheon as designated by the numeral 15.

Suitably mounted on the inner side 12 of the door is a base plate 15' adapted to have detachably fastened thereto by screws 16 or other suitable fastening elements, a casing 80 16'. This casing is of angular formation and has provided therein a graduated channel 17 which leads to a straight channel 18 terminating at one extremity in an enlarged or flared portion 19, provided with shoulders 19'.

The numeral 29 designates a rigid arm which is bifurcated at one extremity as indicated by the numeral 21 and terminates at the opposite extremity in an enlarged portion 22 having formed therein aperture 23, conforming to the shape of the spindle 13, in which aperture the spindle is adapted to rest. It will be evident that a turning of the knob 14 will cause a lateral movement 95 to be imparted to the arm 20, since the grooved escutcheon allows the arm to move freely therein.

Connected to the arm 20 at the bifurcated extremity 21 by a pin or other suitable connecting means 21' is the inner extremity 22' of a longitudinal slideable rod 23' which has integrally formed thereof a collar 24 provided with a shoulder 25, while positioned on the opposite end of the rod is a buffer 26, preferably made of elastic or yielding material. The buffer rod 23' and its integrally formed collar are adapted to move as a unit with the arm 20 when the latter is actuated upon the turning of the handle 14. 100 105 110

The numeral 27 designates a coil spring which encircles the rod 23, and which has one end thereof abutting the shoulder 25 and its opposite end contacting with the base of the 5 buffer 26. This spring upon expansion tends to throw and retain the buffer in the extended position shown to advantage in Figure 1, and thereby affords a means for preventing the slamming or closing of the door.

10 When it is desired to close the door and return the buffer within the casing it is only necessary to turn the knob, and retain a grip on the same, and then the rigid arm having its enlarged aperture portion mounted on the 15 spindle 13 will move laterally within the graduated channel 17 and cause an inward longitudinal sliding movement to be imparted to rod 23', and at the same time the spring will assume a contracted position.

20 When the buffer is returned within the casing, the door can be readily latched by releasing the grip on the knob. Then the latch will enter the keeper and the buffer will be prevented from passing from the casing by its contact with the door jamb.

From the foregoing description taken in connection with the drawings, it will be readily apparent that I have provided a safety attachment which can readily be installed 30 upon various types of doors, and an attachment which is simple in construction, positive in operation, and exceedingly serviceable.

It is to be understood that the form of my 35 invention herewith shown and described, is to be taken as a preferred example of the same, and that various changes in the shape, size and arrangement of parts may be resorted to without departing from the spirit 40 of the invention or the scope of the subjoined claims.

Having thus described my invention, I claim:

1. A safety device for doors comprising 45 a casing mounted on the side of a door in close proximity to the door knob and its spindle, an operating arm disposed within said casing and having one extremity thereof mounted on the spindle and rotatable therewith, a longitudinally movable rod having pivotal connection at one extremity with said arm and having a buffer member mount-

ed on the other extremity thereof, and tension means carried by said rod and adapted to throw the buffer therof into an operative 55 position.

2. A safety device for doors comprising a casing mounted on the side of a door in close proximity to a door knob and its spindle, a base plate fixed to said door and adapted to receive said casing thereon, an arm carried by said spindle and rotatable therewith, a rod connected at one extremity to said arm, a buffer carried on the opposite extremity of said rod, and tension means carried by said 60 rod and adapted to throw the buffer into an operative position.

3. A safety device for doors comprising a casing mounted on the side of a door in close proximity to a door knob and its spindle, 70 said casing having formed therein a graduated channel and a straight channel forming a shoulder, a base plate fixed to said door and adapted to receive said casing thereon, an arm carried by the spindle and rotatable therewith, a rod having a collar formed thereon and connected at one extremity to said arm, said rod provided with a collar, a buffer positioned on the opposite extremity of said rod, and tension means carried by said rod and adapted to throw said buffer into an operative position, said tension means having its degree of expansion limited by the collar on said rod and said 75 buffer.

4. A safety device for doors comprising a casing mounted on the side of a door in close proximity to a door knob and its square spindle, an arm carried by the spindle and rotatable therewith, said arm terminating at one end in enlarged apertured portion adapted to straddle the spindle and terminating at the opposite end in a bifurcated extremity, means carried on the spindle for allowing lateral movement of said arm with 80 in said casing, a rod connected at one end to said arm and adapted for longitudinal movement within said casing upon lateral movement of said arm, a buffer positioned on the opposite end of said rod, and tension means 85 encircling said rod, and adapted to throw said buffer into an extended position.

In testimony whereof I affix my signature
ABE KELLER.
